UNITED STATES PATENT OFFICE.

MATUREN GOLD, OF HAYWARD, OKLAHOMA, AND WILLIAM ARTHUR MONTGOMERY,
OF SOLANO, TERRITORY OF NEW MEXICO.

MINE SAFETY APPARATUS.

1,005,196.

Specification of Letters Patent. Patented Oct. 10, 1911.

Application filed March 16, 1910. Serial No. 549,698.

To all whom it may concern:

Be it known that we, MATUREN GOLD, a citizen of the United States of America, and a resident of Hayward, in the county of 5 Garfield, in the State of Oklahoma, and WILLIAM ARTHUR MONTGOMERY, a citizen of the United States of America, and a resident of Solano, in the county of Mora, in the Territory of New Mexico, have invented 10 certain new and useful Improvements in Mine Safety Apparatus, whereof the following is a specification.

This invention relates to apparatus for supplying air, water and food to mines and 15 other shafts and tunnels.

The objects of the invention are to enable a miner to pass through and work in noxious gases contained within the mine rooms or galleries without injury or danger to himself 20 through suffocation, to supply food and water in case of emergency to miners confined within the mine and to suppress dust and prevent explosions within the mine.

To this end the invention comprises means 25 for supplying air to the miners individually and for tempering the air so supplied, and means for sprinkling the interior of the mine to allay and prevent dust; such means or a part thereof being also adapted for supplying food and water to the miners in cases 30 of accident or emergency.

Figure 1 of the accompanying drawings represents a vertical section of a mine embodying one form of this apparatus. Fig. 2 35 represents a horizontal section on line 2--2 of Fig. 1. Fig. 3 represents on an enlarged scale a side elevation partly in vertical section of this apparatus. Fig. 4 represents a horizontal section on line 4--4 of Fig. 3 40 showing concentric air and water cylinders disposed in the mine shaft and provided with branch pipes leading to the mine entries and rooms. Fig. 5 represents a helmet or hood and the means for attaching it to the body 45 for individual supply of air to the miner.

The same reference numbers indicate corresponding parts in all the figures.

The apparatus in the form in which it is illustrated in the accompanying drawings 50 comprises two pipes disposed one within the other; an outer pipe 10 for water and an inner pipe 20 for air. By this arrangement the temperature of the air supplied to the mine is regulated more or less by the temperature 55 of the water, being cooled in summer

and warmed in winter. For mines which are entered through a vertical shaft, the outer pipe 10 is in the form of a stand pipe vertically disposed in said shaft. Each pipe may be constructed in sections united by any 60 suitable joint couplings. A water supply pipe 15 leads from any suitable source of water supply and connects with the stand pipe 10 near the top thereof. The air pipe 20 is connected with a blower 25 or other 65 means of air supply.

Water pipes as 30 and 35 connect with the stand pipe 10 at the different mine levels and extend through the mine entries being preferably laid underneath the floors 70 thereof. These water pipes are provided at suitable intervals with valved branches as 31 or 36 for the attachment of a hose 40 for sprinkling the mine to allay dust and prevent explosions.

Air branch pipes as 50 and 55 connected with the vertical air pipe 20, pass through the walls of the stand pipe 10 at the different mine levels and extend through the mine entries, being also preferably laid underneath 80 the floors thereof. These branch air pipes are provided with valve air distributing taps 60 and 65 for attachment of helmet hose for the individual supply of air to the miners and with upright distributing pipes 85 as 70 terminating in a mine room and adapted to receive a flexible pipe 75 provided with a spreader 76 movable into position for discharging fresh air near the face of the mine room for supplying a group of 90 mine workers there engaged in undercutting or loading operations.

A helmet 80 is adapted to close over the head and around the neck of the miner, being provided with a flaring collar 81 at its 95 lower end, a vent 82 in its top and a window 83 opposite the eyes. This helmet is provided with valved flexible inlet tubes 84 and 85 for supply of air to the interior thereof. The lower ends of these tubes are 100 provided respectively with couplings 84' and 85', and a belt 86 is connected with said couplings and adapted for application to the waist of the miner. Either of these couplings is adapted to connect with any one of 105 the air pipes 65 of the air distributing pipes 50 or 55. A helmet thus provided with a plurality of air inlet tubes enables the miner to shift from one position to another and to connect with one tap of the air pipe be- 110

fore detaching from the other tap; whereby a constant supply of air is maintained without the encumbrance of long sections of flexible tubes.

- 5 The air supply system may be provided with a safety escape valve and with a pressure gage, placed in the engine room not shown for convenient observation of the engineer.
- 10 The operation of the apparatus is as follows: The main cylinder 10 is supplied with water from any suitable source and the air pipe 20 is supplied with air under pressure sufficient to force it through the apparatus.
- 15 Air is supplied in regulated quantities through the general air distributor 75 to the face of the mine where several miners are at work and when the mine is more or less charged with unpleasant or noxious
- 20 gases the miners are supplied individually with fresh air through the helmets 80 and the individual distributing pipes connecting said helmets with the air supply. By this means mines can be entered after explosions and when filled with gases, and miners rescued and bodies recovered.
- 25 The mine may be kept sprinkled by connecting water distributing pipes with water supply pipes. In case of necessity liquid food or nourishment may be supplied to the miners through the water tube system.

We claim as our invention—

1. The combination of a mine, a system of pipes therein provided with a series of 30 valved taps, means for forcing air through

said pipes, and a helmet provided with an air vent and with a plurality of flexible air inlet pipes having couplings connectible with said taps.

2. The combination of a mine, a system of 40 water pipes therein, a water supply connected therewith, a system of air pipes disposed in said mine, one of said air pipes being inclosed in one of said water pipes, means connected with said air pipes for forcing 45 air therethrough, and separate distributing pipes connected with said systems, and having independent outlets.

3. The combination of a mine, a stand pipe disposed in the vertical shaft thereof, 50 an air pipe disposed in said stand pipe, a branch pipe connected with said stand pipe and provided with means for distributing water at different points within the mine, and a branch pipe connected with said air 55 pipe and provided with means for distributing the air at different points within the mine, the outlets for the water and air being independent of each other.

4. A device for individual supply of air to a miner comprising a helmet provided with an air vent, a window, and a plurality of valved flexible inlet tubes having couplings for suitable connection with an air supply system.

MATUREN GOLD.
